UNITED STATES PATENT OFFICE.

ERNEST B. CROCKER, OF BOSTON, MASSACHUSETTS.

WINDOW-SCREEN.

No. 889,782.

Specification of Letters Patent.

Patented Dec. 25, 1906.

Application filed March 19, 1906. Serial No. 306,715.

To all whom it may concern.

Be it known that I, ERNEST B. CROCKER, of Boston, county of Suffolk, State of Massachusetts, have invented an improvement in 5 Window-Screens, of which the following description, in connection with the accompanying drawings, is a specification, like characters on the drawings representing like parts. This invention relates to roller window-screens, and is intended as an improvement upon the roller window-screen shown in Letters Patent No. 725,319, dated April 14, 1903; and the invention has for its object to simplify and improve the construction of the 15 same in many particulars.

The invention consists in providing improved bearings for the tape-receiving pulleys or drums, which are located at the lower ends of the vertical tape-receiving compartments at the opposite sides of the screen, and also in providing for more easily placing the pulleys or drums in position at the lower ends of said vertical compartments; also, in improved means for connecting the ends of the 20 tapes with the pulleys or drums; also, in an improved form of bottom casing containing the screen, oil and in novel means of attaching the lower ends of the upright guide-plates to the opposite ends of said bottom casing; 25 also, in an improved form of finger-engaging bar at the upper end of the screen and means for holding it securely in place and in improved means for connecting the upper end of the screen with said finger-engaging bar; 30 also, in improved means for supporting the pulleys at the upper ends of the tape-receiving compartments of the guide-plates and for adjusting said pulley-supports to different elevations.

Figure 1 shows in front elevation a roller window-screen embodying this invention. Fig. 2 is a vertical section of the same, taken through one of the tape-receiving compartments on the dotted line 2-2, Fig. 1. Fig. 3 is a vertical section of the same, taken on the dotted line 3-3, Fig. 1. Fig. 4 is a vertical section of the same, taken on the dotted line 4-4, Fig. 3, the bottom casing being removed to expose the screen-roll. Fig. 5 is a detail of 45 the lower end portion of one of the guide-plates. Fig. 6 is a similar view showing the bottom casing in section. Fig. 7 is a detail showing in front elevation the lower end portion of one of the guide-plates and the adjacent portion of the bottom casing. Fig. 8 is 50 a detail showing in cross-section one of the

guide-plates, taken on the dotted line 8-8, Fig. 5. Fig. 9 is a detail showing the means for connecting the bottom casing with the lower end of one of the guide-plates. Fig. 60 10 is a detail showing the manner of connecting the upper edge of the screen to the cross-bar to which the tape is attached and also the finger-engaging bar. Fig. 11 is a detail showing in vertical section the upper edge of 65 the screen and attaching means, taken on the dotted line 11-11, Fig. 10. Fig. 12 is a detail of the cross-bar to which the upper edge of the screen is attached. Figs. 13 and 14 are details of the pulley or drum to which the 70 lower end of the tape is attached. Figs. 15 and 16 are details showing the loop-like ends which are formed on the ends of the tapes. Figs. 17 and 18 are details of the uppermost 75 pulleys over which the tapes pass.

a represents a tubular cylinder or roll upon which the screen *a'* is wound, which is of any suitable length and diameter, the screen being of any suitable construction or a shade being employed in lieu thereof. At each end 80 of the screen-roll *a* a pulley or drum *b* is provided, having a hub which extends into the roll, said hub comprising a cylindrical portion *b'* of lesser diameter than the pulley and a cylindrical portion *b''* of lesser diameter 85 than the portion *b'*. The pulley and hub are made as an integral tubular shell, and the hub of the pulley extends into the screen-roll, the cylindrical portion *b'* thereof loosely fitting the open end of said roll and serving as 90 a bearing therefor and the cylindrical portion *b''* serving as a point of attachment for the outer end of a compensating spring, to be described. The screen-roll is supported and freely revoluble on the hubs of said pulleys or drums. Within the screen-roll two 95 compensating springs *c* and *d* are placed, made as right and left springs, respectively, and disposed at opposite ends of the spring-roll, the inner ends of which are attached to 100 the screen-roll and the outer ends to the hubs of the pulleys or drums, thereby connecting the screen-roll with the pulleys or drums. To positively insure the two oppositely-disposed springs operating in unison, 105 the outer ends of the springs are connected together by a bar *e* or otherwise, said bar being made of suitable length and extending through the screen-roll from end to end thereof, or thereabout.

At the opposite sides of the screen upright 110 guide-plates are provided, which extend

along the sides of the window-casing, being herein shown as formed of sheet metal bent and folded to produce a right-angular passage, in one part of which, as f , the pulleys or drums are placed and in the other part of which, as f' , the edge of the screen runs, the part f constituting a tape-receiving compartment and the part f' a guide-passage for the screen. At the lower end of the tape-receiving compartment of each guide-plate the pulleys or drums b are supported, and, as herein shown, the inner wall of each guide-plate, near its lower end, has a hole f^2 , made large enough to receive the pulley or drum. A stud or pin f^{10} is rigidly secured to the inside of the outer wall of said guide-plate, which projects inwardly and is located at a point coincident with the center of the hole f^2 , and the pulley or drum has fitted or driven into its outer end a circular end piece or cap f^{12} , formed with a circumferential flange f^{13} , which engages the interior of the pulley or drum, and also formed with a central hole through it for the stud or pin f^{10} and with a circular flange f^{14} around said central hole, which extends inwardly and forms a long bearing for the pulley or drum on said stud or pin. This manner of forming the pulleys or drums and for supporting them is simpler than the manner shown in the patent referred to and is more efficient, and the pulleys or drums are more easily placed in position at the lower ends of the vertical tape-receiving compartments of the guide-plates. In each vertical compartment f a metallic tape h is arranged, which passes around a pulley or drum b , which is located at the lower end thereof and which is attached to said pulley or drum, and as a means of attaching the tape h to said pulley or drum a slot h' is formed in the pulley or drum; and a slot h^2 is formed in the flange f^{13} of the end cap, which registers with said slot h' , and the tape passes through said slots, and the end of the tape which terminates within the drum pulley is folded upon itself, as shown in Figs. 15 and 16, and the folded end is bound together and held by a clip f^{150} . The end of the tape is thus provided with an enlargement which prevents it from being withdrawn from the pulley or drum through the aforesaid slots.

The upright guide plates or pieces at the sides of the screen, which are attached to the window-casing, are connected at their lower ends to a bottom casing, and said bottom casing and also the means herein shown of attaching the lower ends of the guide-plates thereto are of novel construction.

The bottom casing is made as a shell and is adapted to contain within it, and thereby inclose the screen-roll, and hence is made to extend from side to side of the window-casing. The bottom casing consists of a circularly-formed portion m , rising from a flat

base m' , having its upper or free edge rolled, as at m^2 , to give to it a finished appearance and additional strength, and a lip m^3 , rising from the rear edge of said base m' , which extends upward a short distance. The base m' and the upturned lip m^3 extend a short distance beyond the circular portion m at each end thereof, and the rolled edge m^2 terminates a short distance from the opposite ends of the circular portion on which it is formed, and both ends of said rolled edge are internally screw-threaded for a short distance. The upturned lip m^3 has near each end a countersunk hole m^4 . The base m has placed upon and secured to it near each end a boss m^5 , which is internally screw-threaded. The base m has also one or more holes m^6 located at any convenient point or points for the escape of any water which may enter the casing. The lower end of each guide-plate is constructed in a novel manner to be attached to said bottom casing. The lower end of each guide-plate rests upon the base m of the bottom casing, and through both walls of the vertical tape-receiving compartment holes f^{15} are punched, which register with each other and which are located opposite the screw-threaded boss m^5 , so that a screw f^{16} may be projected through said walls and into said boss, as shown in Fig. 7. The inner wall of the screen guide-passage terminates a short distance above the lower end of the guide-plate and is formed or provided with a rolled edge f^{17} , and holes are punched through the walls of the tape-receiving compartment opposite the open end of said rolled edge, and the rolled edge is disposed in horizontal alignment with the rolled edge m^2 on the circular portion m , and a screw f^{18} is projected through said holes in the tape-receiving compartment and through the hole in said rolled edge f^{17} and into the open end of the rolled edge m^2 . A conical boss f^{20} is provided on the inner side of the outer wall of the screen guide-passage, which is disposed to occupy a position opposite the countersunk hole in the upturned lip m^3 and which is recessed to receive the projecting portion around said hole m^4 and which is centrally screw-threaded to receive the screw f^{21} , which passes through the hole m^4 . The lower ends of the guide-plates are thus securely attached to the hollow bottom casing.

At the upper edge of the screen a cross-bar is secured, consisting of a right-angularly-formed strip of metal, comprising a vertical portion i and a horizontal portion i' at the upper edge thereof, the former extending a short distance beyond the latter at each end, and the screen extends up next the vertical portion on the inside thereof and is bent over and around the horizontal portion thereof, so that the edge of the screen terminates on top of said horizontal portion. At each end of the vertical portion i of the bar a hole is

punched, as at i^2 , and a clip i^3 is applied to each end of the bar, which embraces the bar and screen thereon, and said clip is secured by a rivet or other means passing through the hole i^2 . The clip i^3 extends a short distance above the bar i to provide a passage through it for a pin i^4 .

A finger-engaging cross-bar is provided, comprising a vertical portion i^5 , which is adapted to rest against the screen in front of the portion i , and a bent or folded portion i^6 at right angles to the portion i^5 , which is adapted to embrace the horizontal portion i^7 and screen, which is folded thereon, to thereby hold the edge of the screen in place and provide a finished edge. The rear edge of the folded portion i^6 is rolled, as at i^7 , and said rolled edge occupies a position in alignment with the passages through the clips i^3 , so that the pins i^4 , which extend through said passages, may enter the open ends of the rolled edge i^7 , and thereby hold the finger-engaging bar in position. The pins i^4 project outward a short distance from the clips i^3 , and to said outwardly-projecting ends the ends of the tapes h are connected. The ends of the tapes h which are connected to the pins are folded upon themselves in loop-like manner, as shown in Figs. 15 and 16, and held fast by a clip f^{16} , substantially the same as the opposite ends of the tapes are formed; but in the present instance the loop-like portions are employed for the purpose of receiving the pins i^4 , as shown in Fig. 16. The clips i^3 , which are attached to the ends of the cross-bar and which hold the screen thereon, are made quite thin, so as to enter and slide freely in the screen-receiving passages of the guide-plates.

At the upper ends of the tape-receiving compartments f of the upright guide-plates pulleys g are provided, over which the tapes h pass, and said pulleys are herein shown as shells struck up from sheet metal and mounted on studs g^1 , projecting laterally from plates g^2 , which are supported in a manner to provide for adjustment to different elevations. The plates g^2 each have a pair of ears g^3 , formed with threaded holes through them, adapted to receive adjusting-screws g^4 . Caps g^5 , consisting of metallic shells, are mounted upon the upper ends of the upright guide-plates, being supported by said plates, and the adjusting-screws g^4 pass through holes in said caps and enter the screw-threaded ears g^3 . The pulley-supporting plates are therefore supported by and upon said adjusting-screws, and by turning said screws said plates may be adjusted to different elevations. At or near the upper end of each guide-passage for the screen a stud or post e is provided, which acts to hold the side walls of the guide-passage suitably spaced apart and also as a stop to limit the upward movement of the screen.

Having thus described my invention, what I claim as new, and desire to secure by Letters Patent, is—

1. In a rolling window-screen, the combination of a tubular screen-roll, having a screen thereon, a tubular shell at each end of said roll having a cylindrical tape-receiving portion and a cylindrical portion fitting the end of said roll, end pieces fitted into each tubular shell having a central tubular bearing, an upright guide-plate at each end of the roll having a guide-passage for the screen and a tape-receiving compartment, the inner wall of said compartment having a hole through which projects the tape-receiving portion of said shell, and the outer wall of said compartment having a stud coincident with the center of said hole, which receives upon it the end piece, substantially as described. 70

2. In a rolling window-screen, the combination of a tubular screen-roll having a screen thereon, compensating springs within said roll, a tubular shell at each end of said roll having a cylindrical portion fitting the end of the roll and a cylindrical portion of 75 lesser diameter at the inner end thereof to which one of the compensating springs is connected, and a cylindrical portion of greater diameter at the outer end thereof which projects from the roll and receives upon it the tape, a circular end piece fitted into the outer end of the shell having a central tubular bearing, an upright guide-plate at each end of the roll having a guide-passage for the screen, and a tape-receiving compartment into which the tape-receiving portion 80 of said shell projects, and a stud projecting inward from the outer wall of said compartment which receives upon it said end piece, substantially as described. 85

3. In a rolling window-screen, the combination of a tubular screen-roll having a screen thereon, a tubular shell at each end of said roll having a cylindrical tape-receiving portion and a cylindrical portion of lesser diameter than the tape-receiving portion fitting the end of said roll, an end piece fitted into each tubular shell having a central tubular bearing, an upright guide-plate at each end of the roll having a guide-passage for the screen, and a tape-receiving compartment, the inner wall of said compartment having a hole through which projects the tape-receiving portion of said shell and the outer wall of said compartment having a stud coincident 90 with the center of said hole which receives upon it the end piece, the tubular shells being held from longitudinal movement in one direction by the roll and in the opposite direction by the outer walls of the tape-receiving compartments of the guide-plates, substantially as described. 95

4. In a rolling window-screen, the combination of a screen-roll having a screen thereon, a hollow bottom casting containing it, 100

1
comprising a flat base and a circular portion rising from it, which is formed integral therewith, and guide-plates at the opposite ends of said bottom casing which are attached thereto and which have guide-passages for the edge of the screen, substantially as described.

5. In a rolling window-screen, the combination of a screen-roll having a screen thereon, a bottom casing containing it, comprising on, a bottom casing containing it, comprising a base and a circular portion rising from it having a rolled edge, a threaded boss on the base, and guide-plates at the opposite ends of said bottom casing having holes through them for screws which pass through said holes and enter the open end of said rolled edge and also the threaded boss, substantially as described.

6. In a rolling window-screen, the combination of a screen-roll having a screen thereon, a bottom casing containing it comprising a base and a segmented portion rising from it, a threaded boss on said base and guide-plates at the opposite ends of said bottom casing having holes through them for screws which pass through said holes and engage the threaded bosses, substantially as described.

7. In a rolling window-screen, the combination of a screen-roll having a screen thereon, upright guide-plates at the opposite ends thereof having tape-receiving compartments, and guide-passages for the screen, a cross-bar at the upper end of the screen comprising a horizontal portion and a vertical portion extending beyond the ends of the horizontal portion, clips embracing the extended ends of the vertical portion and a screen thereon, which are secured to said cross-bar and thereby fix the screen thereto, said clips entering and sliding freely in the vertical guide-passages provided in the guide-plates, substantially as described.

8. In a rolling window-screen, the combination of a screen-roll having a screen thereon, upright guide-plates at the opposite ends thereof having tape-receiving compartments and guide-passages for the screen, an angular cross-bar at the upper end of the screen which receives upon it the end of the screen, an angular finger-engaging bar on said cross-bar with the screen interposed between said finger-engaging bar and cross-bar, means for attaching the screen to the cross-bar and means for connecting the finger-engaging bar also with said cross-bar, whereby the assembled parts are all connected together, substantially as described.

9. In a rolling window-screen, the combination of a screen-roll having a screen thereon, upright guide-plates at the opposite ends thereof having tape-receiving compartments and guide-passages for the screen, an angular cross-bar at the upper end of the screen which receives upon it the end of the screen, an angular finger-engaging bar placed upon

said cross-bar with the screen interposed between said finger-engaging bar and cross-bar, having a rolled edge, clips embracing the ends of the cross-bar and screen, and pins extended through said clips and into the open ends of the rolled edge of the finger-engaging bar, substantially as described.

10. In a rolling window-screen, the combination of a screen-roll having a screen thereon, upright guide-plates at the opposite ends thereof having tape-receiving compartments and guide-passages for the screen, an angular cross-bar at the upper end of the screen, which receives upon it the end of the screen, an angular finger-engaging bar placed upon said cross-bar with the screen interposed between said finger-engaging bar and cross-bar, having a rolled edge, clips embracing the ends of the cross-bar and screen, and pins extended through said clips and into the open ends of the rolled edge of the finger-engaging bar, and tapes contained in the tape-receiving compartment, the ends of which are connected to said pins, substantially as described.

11. In a rolling window-screen, the combination of a screen-roll having a screen thereon, upright guide-plates at the opposite ends thereof, having tape-receiving compartments and guide-passages for the screen, an angular cross-bar at the upper end of the screen which receives upon it the end of the screen, an angular finger-engaging bar placed upon said cross-bar with the screen interposed between said finger-engaging bar and cross-bar, having a rolled edge, clips embracing the ends of the cross-bar and screen, pins extended through said clips and into the open ends of the rolled edge of the finger-engaging bar, and tapes contained in the tape-receiving compartment having loop-like ends which receive the pins projecting from the clips, substantially as described.

12. In a rolling window-screen, the combination of a screen-roll having a screen thereon, upright guide-plates at the opposite sides of the screen having tape-receiving compartments and guide-passages for the screen, pulleys at the lower ends of said tape-receiving compartments connected with said screen-roll, tapes passing around said pulleys, pulleys at the upper ends of said tape-receiving compartments over which said tapes pass and adjustable supports for said uppermost pulleys, substantially as described.

13. In a rolling window-screen, the combination of a screen-roll having a screen thereon, upright guide-plates at the opposite sides of the screen having tape-receiving compartments and guide-passages for the screen, pulleys at the lower ends of said tape-receiving compartments connected with said screen-roll, tapes passing around said pulleys, pulleys at the upper ends of said tape-receiving compartments over which said tapes pass,

supporting-plates for said pulleys and caps mounted on the upper ends of said guide-plates with which said supporting-plates are connected, substantially as described.

- 5 14. In a rolling window-screen, the combination of a screen-roll having a screen thereon, upright guide-plates at the opposite sides of the screen having tape-receiving compartments and guide-passages for the screen, pulleys at the lower ends of said tape-receiving compartments connected with said screen-roll, tapes passing around said pulleys, pulleys at the upper ends of said tape-receiving compartments over which said tapes pass,

supporting-plates for said uppermost pulleys 15 having screw-threaded ears, caps mounted on the upper ends of said guide-plates and screws projecting downward from said caps which engage said screw-threaded ears, substantially as described.

In testimony whereof I have signed my name to this specification in the presence of two subscribing witnesses.

ERNEST B. CROCKER.
